CLAIM

The ornamental design for an infant teether, as shown and described.

DESCRIPTION

FIG. 1 is a top perspective view of a first embodiment of an infant teether;

FIG. 2 is a bottom perspective view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a right side elevation view thereof; and

FIG. 8 is a left side elevation view thereof.

FIG. 9 is a top perspective view of a second embodiment of an infant teether;

FIG. 10 is a bottom perspective view thereof;

FIG. 11 is a top plan view thereof;

FIG. 12 is a bottom plan view thereof;

FIG. 13 is a rear elevation view thereof;

FIG. 14 is a front elevation view thereof;

FIG. 15 is a right side elevation view thereof; and,

FIG. 16 is a left side elevation view thereof.

The even-length broken lines in the drawings depict portions of the infant teether that form no part of the claimed design.

1 Claim, 12 Drawing Sheets(56)
